INVENTOR

Olaf Bakke,

ATTORNEY

UNITED STATES PATENT OFFICE.

OLAF BAKKE, OF NEW ENGLAND, NORTH DAKOTA.

GREASE-CUP.

1,285,588.

Specification of Letters Patent. Patented Nov. 26, 1918.

Application filed May 16, 1918. Serial No. 234,977.

To all whom it may concern:

Be it known that I, OLAF BAKKE, a citizen of the United States, residing at New England, in the county of Hettinger and State of North Dakota, have invented certain new and useful Improvements in Grease-Cups, of which the following is a specification.

This invention relates to improvements in grease cups, and more particularly to that type adapted for feeding grease or other lubricants of a thick character and in which the cup is formed of two parts having threaded engagement with each other to provide for applying pressure to the lubricant to insure the feed thereof to the bearing to which the cup is connected.

In connecting grease cups of this character to bearings and especially to bearings of automobiles which are subjected to considerable vibration, the parts work loose and become lost or cease to exert pressure on the lubricant, and it is to overcome this objection that the device constituting this invention is devised.

Another object is to provide a grease cup which may be as easily adjusted as the ordinary cup and when adjusted, the movable part may be easily locked in adjusted position by a simple locking device carried by the cup cap.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a side elevation of a grease cup constructed in accordance with this invention with the cap shown in locked position thereon,

Fig. 2 is a similar view taken in a plane at right angles to Fig. 1 with the cap shown slightly unscrewed, and

Fig. 3 is a plan view showing the locking element in operative position.

In the embodiment illustrated, a grease cup 1 is shown provided at one end with the ordinary threaded stem 2 for connection with the bearing and is externally

threaded on its upper enlarged end as shown at 3 to receive an internally threaded cup cap 4 which is adapted to hold the lubricant and to be screwed downwardly on the body 60 portion to force the lubricant out.

The cap 4 is provided on its cup with a pair of laterally spaced lugs 5 which incline downwardly in opposite directions gradually merging into the cap and preferably being formed integral therewith. By so constructing these lugs the locking element presently to be described may easily ride up on either one of them and be dropped between them in the seat formed by their 70 opposed ends.

This cap 4 is provided on one side wall with laterally extending vertically spaced and aligned bearing ears 6 which are designed to receive an L-shaped locking member 7. 75 This locking member 7 is composed of heavy spring wire and the terminal or free end of the arm which extends through the bearing 6 is bent at an oblique angle to form a finger 10 which when in operative position is designed to engage the face of the cup proper as shown clearly in Figs. 1 and 2. The short arm 8 of the member 7 is extended horizontally and adapted to swing over the upper face of the cup of cap 4, the 85 lugs 5 on said cap being arranged in the path of said arm so that when the arm reaches the space or seat between these lugs it will drop thereinto and thus lock the cap to the cup as is shown clearly in Fig. 1. The free 90 end of arm 8 has its terminal bent to form a loop 9 designed as a handle for operating the locking element.

In use, the cup is filled in the ordinary manner and the cap 4 is turned on the stem 95 portion to exert the pressure on the lubricant. When the desired pressure has been obtained, the locking member 7 is turned in the bearing 6 by grasping the handle 9 which causes the arm 8 to swing over the 100 top of cap 4 and to ride up on one of the inclined lugs 5 until it reaches the highest point thereof which is adjacent the space between the lugs and when said arm passes over this end, it will drop into the seat 105 formed between the lugs and owing to its resiliency will closely hug the top of the cap and be held by the lugs against turning in either direction until it has been manually released from this position. When this arm 110 is so locked the finger 10 will have gripping engagement with the inclined face of the

body proper 1 as shown in Fig. 1, thus exerting a clamping action on the cap and holding it securely against turning on the body portion of the cup.

5 The foregoing description and the drawings have reference to what may be considered the preferred or approved form of my invention. It is to be understood that I may make such changes in construction and 10 arrangement and combination of parts, materials, dimensions, etc., as may prove expedient and fall within the scope of the claimed invention.

Having thus fully described my invention, 15 what I claim as new and desire to secure by Letters Patent is:—

1. A grease cup comprising a fixed member, a rotatable cap movable on the fixed member, and rotatable means carried by said 20 cap for engaging the fixed member to lock the cap against rotation.

2. A grease cup comprising a fixed member, a cap rotatable thereon, a rotatable rod carried by said cap, and means on said rod 25 for clampingly connecting the cap to the cup.

3. A grease cup comprising a fixed member, a cap rotatable thereon, and having laterally extending vertically spaced and 30 alined bearings, an L-shaped locking member having one arm mounted on said bearings with its free end extending below the bottom of the cap and shaped to engage the cup

Copies of this patent may be obtained for five cents each, by addressing the "Commissioner of Patents, Washington, D. C."

when in operative position, and means carried by the cap for locking the short arm 35 of said member in operative position.

4. A grease cup comprising a fixed member, a cap rotatable thereon, and having laterally extending vertically spaced and alined bearings, an L-shaped locking member 40 having one arm mounted on said bearings with its free end extending below the bottom of the cap and shaped to engage the cup when in operative position, and a seat on the top of said cap to receive and hold the short arm of said locking member when 45 in operative position.

5. A grease cup comprising a fixed member, a cap rotatable and adjustable thereon, an L-shaped locking rod mounted for rotation on said cap with one arm positioned to swing parallel with the top of the cap and in close proximity thereto and the other arm having an obliquely disposed finger positioned to engage the fixed member of the 55 cup when in operative position, and a pair of laterally spaced lugs inclined downwardly in opposite directions to form a seat between them to receive the arms of said locking element which moves over said top. 60

In testimony whereof I affix my signature in presence of two witnesses.

OLAF BAKKE.
